UNITED STATES PATENT OFFICE.

ELIAL M. STAPLES, OF ELIZABETH, NEW JERSEY.

HOLDER.

SPECIFICATION forming part of Letters Patent No. 580,148, dated April 6, 1897.

Application filed September 8, 1896. Serial No. 605,076. (No model.)

To all whom it may concern:

Be it known that I, ELIAL M. STAPLES, of Elizabeth, in the county of Union and State of New Jersey, have invented an Improvement in Holders, of which the following description, in connection with the accompanying drawings, is a specification, like letters on the drawings representing like parts.

It is the object of my invention to provide 10 an improved holder which will maintain itself in proper general position to be placed around the handle of a flat-iron, tea-pot, or other vessel which is to be lifted from the fire, said holder being mainly composed of non-heat-conducting material and being also provided 15 with pockets or guards to inclose the fingers and thumb of the hand, in order to more effectually prevent them from being burned by the heat or by contact with the hot handle.

20 The details of construction and further advantages of my invention will appear in the course of the following description thereof.

In the drawings, Figure 1 is a perspective view showing my improved holder in use. 25 Fig. 2 is a top plan view thereof; and Fig. 3 is a central transverse section taken on the line 3 3, Fig. 2.

In constructing my improved holder I superimpose on top of each other a large number 30 of sheets of non-heat-conducting material, such as paper, and stitch them together by a longitudinal row of stitches a to constitute a body a' . The layers of paper are then curved to the desired form and a second row of 35 stitches a^2 is stitched approximately parallel to the first row of stitches and adjacent the other edge of the layers of non-heat-conducting material. More rows of stitches may be provided, if desired. These stitches serve 40 to permanently maintain the layers in the curved form desired for the finished product. A piece of suitable material b , such as tough cotton or felt, cut to the shape of the holder, is then placed below or within the curved body 45 a' of non-heat-conducting material, the two being joined together by several rows of stitches b' . Another piece of cotton, felt, or other suitable material b^2 to withstand extended use is placed over the body a' and other narrow 50 side pieces c , of felt or other material, are placed at either side, as indicated best in Fig. 3, and the whole is secured or bound together

at the bottom edge d and at either end d' . The side pieces are permitted to bulge at the middle portion slightly away from the body, 55 so as to constitute pockets for the protection of the thumb and fingers in grasping the holder. The upper edges of the pocket may be suitably bound, as at e .

In use the holder, by reason of its permanent curved shape, is always ready to be grasped in proper position by the hand, and by reason of its inclosed non-heat-conducting body portion there is a minimum of heat transmitted to the hand, so that the latter is kept 60 cool, thus avoiding roughness and cracking of the skin by the heat. The fingers and thumb being inclosed within the pockets at either side of the holder cannot possibly come into contact with the hot metal of the flat-iron or 65 other utensil being held, so that all danger of accidental burning is removed.

The body of the holder being composed of a large number of layers stitched together, as indicated, tends to maintain itself in one 75 curved position, so that as soon as the grasp on the handle being carried is released the holder automatically removes itself from close contact with the handle and recovers its original or normal position.

I am aware that it has been proposed to make a holder and shield in curved form having a coating of plaster-of-paris; and also I am aware that paper has been used in flat layers as a lining to a holder; but I am not 85 aware that it has ever been proposed to make a holder having a permanent curvature automatically maintained when the grasp of the hand is released.

By stitching together a large number of 90 sheets of paper, as I have above described in my invention, first by one line of stitches in a flat position and then again by other lines of stitches stitching them together in a curved position, not only is the mass of paper held 95 compactly and properly in position, but the curvature of the holder is permanent, no matter how much the holder may be pinched together or flattened in its use thereafter.

Having fully described my invention, what 100 I claim, and desire to secure by Letters Patent, is—

As an article of manufacture, a holder comprising a body composed of a plurality of lay-

ers of paper, stitched together to form a permanently-curved body said body automatically resuming its normal shape when bent either inwardly or outwardly, a piece of fabric being stitched to the inner or under side of said body, another piece of fabric inclosing the body on the upper side thereof and secured to said inner piece of fabric at the edges thereof, and pockets at the sides of said holder

to contain respectively the thumb and fingers of the hand, substantially as described.

In testimony whereof I have signed my name to this specification in the presence of two subscribing witnesses.

ELIAL M. STAPLES.
